UNITED STATES PATENT OFFICE.

ALBERT SCHNABEL, OF OTTINE, TEXAS.

SUPPORT FOR COTTON-PICKERS' SACKS.

1,168,429.

Specification of Letters Patent. Patented Jan. 18, 1916.

Application filed March 19, 1915. Serial No. 15,534.

To all whom it may concern:

Be it known that I, ALBERT SCHNABEL, a citizen of the United States, residing at Ottine, in the county of Gonzales and State of Texas, have invented certain new and useful Improvements in Supports for Cotton-Pickers' Sacks; and I do hereby declare the following to be a full, clear, and exact description of the invention, such as will enable others skilled in the art to which it appertains to make and use the same.

This invention relates to supports for cotton pickers' sacks, and one of the principal objects of the invention is to provide means to support the lower end of the bag and to take the wear that usually comes upon the bag in dragging the same over the ground in picking cotton.

Another object of the invention is to provide a box-like support to which the lower end of the bag is connected, said support being formed of sheet metal of the desired gage and of any suitable size, said support having means for detachably connecting a bag thereto and the bag being attached to or carried by the cotton picker, while the support takes the wear that would occur upon the bag if dragged upon the dirt through the cotton field.

The foregoing and other objects may be attained by means of the construction illustrated in the accompanying drawing, in which—

Figure 1 is a side elevation of a cotton bag and support made in accordance with this invention, Fig. 2 is a transverse sectional view taken on the line 2—2 of Fig. 1, looking in the direction indicated by the arrow, Fig. 3 is a perspective view looking at the upper side of the bag support, and Fig. 4 is a top plan view of the same.

Referring to the drawing, the numeral 1 designates as an entirety, a sheet metal support for a cotton picking bag 2. The support is made of sheet metal of the required gage, and may be stamped up into form having a flat bottom 3, side flanges 4 of the desired height, an end flange 5, and an inclined front end 6. The side flanges 4 may extend around the flange 5 and be secured by the lugs 7, or the device may be stamped up of sheet metal of the desired gage with-

out overlapping parts. The front portion 6 is provided with lugs 8 which overlap the side flanges 4.

The bag 2 is provided with a fabric tube 9 stitched or connected underneath the same at some distance from its closed end 10, said fabric tube being open at its opposite ends and extending partially across the bottom of the bag. A strip of metal 11 is pivoted at 12 near the front end 6 of the support, and at the opposite side of the support is a sheet metal keeper 13 for the end of the pivoted strip 11, and a spring tongue 14 secured to the bottom of the support has its end extending beyond the keeper 13 and underneath the same, so that the end of the strip 11 when engaged with the keeper 13 will not be accidentally disconnected therefrom. The strip 11 extends through the fabric tube 9, thus holding the bag detachably within the support 1.

From the foregoing it will be obvious that the bag is connected in any suitable manner to the cotton picker, and that as he picks the cotton and drags the bag along on the ground the bag will not be destroyed owing to the protection given to it by the support 1.

Various changes may be made in the details of construction without departing from the spirit and scope of the invention as defined in the claims.

What is claimed is:—

1. A cotton picker's bag support comprising a metal box having a strip of metal pivotally connected near its front end, and a keeper for the end of said pivoted strip, and a bag having a fabric tube connected to the lower side thereof to be engaged by said strip.

2. A cotton picker's bag support comprising a metal box having side and end flanges, and a pivoted holder for a bag, said holder being detachably connected to a spring keeper, and adapted to pass through a fabric tube connected to the lower side of the bag.

In testimony whereof I affix my signature in presence of two witnesses.

ALBERT SCHNABEL.

Witnesses:

V. E. HOWELL,
A. FRESHAGENS.
